UNITED STATES PATENT OFFICE.

EDWARD A. DIERKES, OF CHICAGO, ILLINOIS.

CURTAIN-STRETCHER FRAME.

1,175,412.

Specification of Letters Patent. Patented Mar. 14, 1916.

Application filed May 1, 1915. Serial No. 25,317.

To all whom it may concern:

Be it known that I, EDWARD A. DIERKES, a citizen of the United States, and a resident of Chicago, in the county of Cook and State 5 of Illinois, have invented certain new and useful Improvements in Curtain-Stretcher frames, of which the following is a specification.

This invention relates to devices on which 10 lace curtains are secured, while wet, for the purpose of allowing said curtains to dry; to thereby give said curtains the appearance of having been laundried; and said devices are commonly known in the trade as curtain 15 stretchers.

The object of this invention is to obtain a curtain stretcher frame on which curtains can be readily secured, by means of pins which are or may be properly positioned to 20 engage with a determined part or figure of said curtains, so that when said curtains are taken from the device a smooth appearance will be presented, particularly at the exposed, (or lower) end of said curtain, when 25 the same is properly hung before a window or other aperture, or thing.

An additional object is to obtain a device, of the kind described, which can be readily made rectangular in shape, and of proper 30 size, so that the curtain which has been stretched thereon, and dried, will present a regular and desired appearance.

Additional objects are to obtain a device 35 of the kind described which can be readily put into condition for use by persons not particularly skilled in mechanics; a device which is easily understood; which is economically made, not liable to break, and is durable.

In the drawings accompanying and forming a part hereof Figure 1 is a top plan view 40 of a curtain stretcher frame embodying the invention, with a portion of a curtain in place thereon. Fig. 2 is a fragmentary end 45 elevation of said frame. Fig. 3 is a perspective of a metal corner which forms an element of the curtain stretcher frame. Fig. 4 is a perspective of an additional metal corner which also forms an element of the device. Fig. 5 is a perspective of a connector 50 element of the device. Fig. 6 is an end elevation of the connector element which is illustrated in detail in Fig. 5 and a side elevation of the head member attached thereto,

(also illustrated in Fig. 2). Fig. 7 is a pin 55 retaining strip, forming an element of the device. Fig. 8 is a perspective of one of the pins of the device, and Fig. 9 is a perspective of one side of the head member of 60 the device.

A reference character applied to designate a given part indicates said part throughout the several figures of the drawing, wherever the same appears.

A, A¹, are the side rails of the frame, and B, B¹ are the end rails. Side rails A, A¹ are made in parts, or pieces (a, a¹), which are joined together by connector C, when the device is set up for use, and which are separated when the device is to be stored, or 70 shipped. Connector C is secured to part a¹ of said rails by means of pins or rivets D, and when set up for use the part a is secured in said connector by the pin d. Connector C is made of sheet metal bent up to obtain the 75 body part c¹, flanges c², c³, and c⁴ on one edge of said body part, and flange c⁵ on the other edge of said body part. Flanges c² and c³ are in planes parallel to the sides of 80 parts a, a¹ of rails A, A¹; the body part c¹ in a plane parallel with the under side of said parts a, a¹; and the flange c³ is in a plane parallel with the top or upper side of said parts a, a¹. Flange c⁵ extends into groove a² of parts a, a¹. The several flanges 85 and the body part of connector C fits closely to the parts a, a¹ of the rails A, A¹.

E is a slidable connector which is provided with the body part and the several flanges of connector C, and said body part 90 and flanges are therefore lettered c¹, c², c³, c⁴ and c⁵, (see Fig. 6). Connectors E are secured in an adjusted position on the end rails B, B¹, by pins F.

G, G¹, are legs which are adapted to support the side and end rails of the device, and said legs are removably attached to the end rails B, B¹, by means of the sheet metal head H; said head being secured to connectors E by means of pivot h. Sheet metal 100 head H is designed to be permanently attached to connector E, by means of said pivot h, and the legs G, G¹ are connected to said head by merely forcing them thereto, endwise. Head H is made of duplicate parts 105 (see Fig. 9) which are attached or secured together by the rivets or bolts h¹. I, I¹ and J, J¹, are corner pieces, which

adjustably connect the side rails A, A¹ to the end rails B, B¹. Corner pieces I, I¹, are rights and lefts; as are also corner pieces J, J¹, and but one of said corner pieces are illustrated in detail, in Figs. 3 and 4. Corner pieces I, I¹, (Fig. 4) permit the adjustment of the side rails relative to the end rail B; while corner pieces J, J¹, permit the adjustment of the side rails relative to the end rail B¹, and also permit the adjustment of said end rail relative to the side rails. That is, the adjustment of the side rails to each other (and on the end rails) to accommodate different widths of curtains, is permitted by all the corner pieces; while adjustment of the end rails to accommodate the length of the curtain must be done wholly by sliding corner pieces J, J¹, on the side rails. From this variation in the construction of the corner pieces the end rail B is in the same plane as the side rails; while the end rail B¹ is in a different plane from said side rails. It therefore occurs that by attaching the end of the curtain which is to be exposed to view, when the curtain is hung, to the end rail B, that end of the curtain will be perfectly smooth; that is, in a determined plane; while the other end of said curtain the lower end as illustrated in Fig. 1 will have its corners and its end in a different plane.

End pieces I, I¹, are made of sheet metal which is bent up on two of its edges to obtain the same body part and flanges as connectors C and E, and said body part and flanges are lettered the same as in said connectors, being c¹, c², c³, c⁴, and c⁵, respectively. End pieces J, J¹, respectively, have additional bends to obtain the flange c⁶, (Fig. 3), and body part c⁷. Body part c⁷ is in a different plane from body part c¹, but is parallel thereto.

K K, are grooves formed in the side walls of a groove which extends longitudinally in side rails A, A¹, and end rails B, B¹, and L, L, are metal plates in said grooves K. Plates L are thus spaced from the bottom of the longitudinally extending grooves and are parallel to said bottom. Metal plates L are respectively provided with slots M, and N.

P are bent pins which are located in slots M. Pins P are provided with heads p, which are adapted to move in said longitudinally extending grooves when parts p¹ of said pins are in said slots M, and which are not slideable in said longitudinally extending grooves when parts p¹ of said pins are in slots N. The width of said longitudinally extending grooves is sufficient to permit lateral movement of pins P when part p¹ of said pins are in grooves N. By this construction the pins can be moved sufficiently to permit attachment of the curtains thereto at a proper, or suitable, place on

said curtains, while at the same time said pins are not movable after the curtain is attached thereto.

X is a portion of a curtain.

The operation of the device is; the several side and end rails are slid in the corner pieces to obtain a suitable frame for the curtain which is to be placed thereon, and then the cotter pins F are forced into and through the holes f in said corner pieces and rails. The side rails are connected by connectors C, and secured by like cotter pins. The connectors E are moved on the end rails to about midway of the frame, and then secured by like cotter pins. The edges of the curtain which is to be stretched are then brought into engagement with the pins P, and secured thereto.

In using the device for small curtains parts a of the side rails may be used, omitting parts a¹, in which case the corner pieces J, J¹ are attached to said parts a.

I claim;

1. In a curtain stretcher frame, side and end rails, respectively provided with grooves on the upper faces thereof, in combination with corner pieces respectively made of sheet metal bent to obtain body parts in parallel planes, joined by a flange integral with an end of one of said body parts, and a side of the other body part, said body parts lying on opposite sides of the connecting flange, each of said body parts bent on one side thereof to obtain flanges at right angles to said body parts, additional flanges parallel to said body parts, and adapted to fit to the upper faces of said rails, and flanges adapted to movably fit said grooves in said rails; whereby said rails may be slid into position in different planes in said corner pieces, and means to secure said rails in said position in the corner pieces.

2. In a curtain stretcher frame, side and end rails in combination with corner pieces, said rails respectively provided with longitudinally extending grooves on the upper side thereof, metal plates in said grooves spaced from and parallel with the bottoms thereof, said plates provided with slots and with lateral slots communicating therewith, and pins in said grooves, said pins extending through said slots, and provided with heads laterally and longitudinally movable in said grooves and said pins also adjustably movable in said first named slots to fit in a desired one of said lateral slots.

3. In a curtain stretcher frame, side and end rails, in combination with corner pieces, connectors on said side rails and additional connectors on said end rails, said side rails consisting of a plurality of parts joined together by the connectors thereon, said corner pieces consisting of sheet metal bent to obtain a central body part and flanges adapted to fit to the sides of said rails, and a head

having inclined sockets pivotally attached to the connector on said end rails, respectively, with bars adapted to be forced into said head, to form legs supporting said frame.

4. In a curtain stretcher frame, side rails consisting of a plurality of parts, and end rails, said rails provided with grooves on the upper sides thereof, in combination with connectors adapted to join said parts of the side rails together, and additional connectors on said end rails, a head having inclined

sockets pivotally connected to said additional connectors, and bars adapted to be forced into said head to form legs supporting said frame, all said connectors comprising a body part, a flange on one edge of said body part, an additional flange parallel to said body part, and a flange adapted to fit in said grooves. 15

EDWARD A. DIERKES.

In the presence of—

CHARLES TURNER BROWN,
EDWARD G. JACKER.
